DESIGN FOR A BACK PANEL FOR A FUR COAT

Harold A. Reich, New York, N. Y.

Application June 6, 1939, Serial No. 85,364

Term of patent 7 years

To all whom it may concern:

Be it known that I, Harold A. Reich, a citizen of the United States of America and residing at Borough of Manhattan, city, county, and State of New York, have invented a new, original, and ornamental Design for a Back Panel for a Fur Coat, of which the following is a specification, reference being had to the accompanying drawing, forming part thereof.

Fig. 1 illustrates in elevation the back expanse of a back panel for a fur coat embodying my invention;

Fig. 2 is a vertical sectional view on line 2—2 of Fig. 1;

Fig. 3 is a horizontal sectional view on the line 3—3 of Fig. 1.

The design is characterized by the arrangement of rows of fur pelts in fluted formation so that the backs of the individual pelts are disposed in the center of the flutes of each row, and the respective sides of the individual pelts lie in the hollows of the flutes, substantially as shown.

I claim:

The ornamental design for a back panel for a fur coat, substantially as shown and described.

HAROLD A. REICH.
